UNITED STATES PATENT OFFICE.

AMOS H. SMITH, OF NEW YORK, N. Y., ASSIGNOR TO AMERICAN BANK NOTE COMPANY,
A CORPORATION OF NEW YORK.

NUMBERING-HEAD.

1,213,286.

Specification of Letters Patent. Patented Jan. 23, 1917.

Application filed May 13, 1915. Serial No. 27,776.

To all whom it may concern:

Be it known that I, AMOS H. SMITH, a citizen of the United States, residing in the borough of Bronx, city of New York, county of Bronx, and State of New York, have invented certain new and useful Improvements in Numbering-Heads, of which the following is a specification, reference being had therein to the accompanying drawings, 10 which form a part thereof.

My invention relates to numbering heads and more particularly to a type thereof wherein the digit wheels are positively locked against movement excepting at those 15 intervals when they are to be rotated in transferring from a wheel of one denomination to the wheel or wheels of succeeding denominations.

Numbering heads of the character to 20 which my invention relates, comprise a sequence of digit wheels adapted to be successively actuated in arithmetical progression, the carrying operation, or transferring, from a wheel of one denomination to the wheel of 25 the next denomination occurring automatically at intervals as determined by the actuation of the machine. The digit wheels are actuated by means of a vibratory member and means are provided whereby each of the 30 wheels is held against movement in one direction during one movement of said actuating mechanism while being free to turn in the other direction with said mechanism. In numbering heads of this character, particularly when actuated at high speeds, there 35 is a tendency of adjacent wheels to bind by reason of the accumulation of ink between the wheels, and the main object of the invention is to provide means whereby all of the 40 wheels except those which must be turned in the normal actuation of the machine, will be locked against movement in either direction and thus prevent accidental skipping of the machine.

45 In a machine made in accordance with my invention, each of the digit wheels of a denomination above the units wheel, is normally locked against movement in either direction, means being provided whereby the locking mechanism for each wheel will be rendered inoperative when said wheel is to be turned. The controlling means for this locking mechanism is actuated from the wheel of next lower denomination thus insuring the timely release thereof. I also

provide means whereby all of the wheels may be simultaneously released to facilitate the setting of the head.

The construction of the head is such that my invention may be applied thereto without increasing its dimensions, so that the invention may be applied to type high numbering heads for use in power driven machines without modification of the machine. 60

In numbering heads of this type, each of the digit wheels is ordinarily provided with a ratchet wheel coöperating with which is a holding pawl having the two-fold function of alining the wheels and preventing a turning movement thereof during one movement 65 of the actuating means. These pawls are spring pressed and are adapted to be forced outwardly as the digit wheel, and its ratchet wheel, are turned. By providing means acting upon each of said pawls which will prevent its movement by its ratchet wheel, said ratchet wheel and also its digit wheel, may be positively locked against movement except at such times when the wheel acting upon said pawl is made inoperative with relation thereto. The construction and arrangement of the means acting upon the pawls are such that each of them, acting upon the pawl of one wheel, will be actuated to release said pawl when the adjacent wheel 70 has the character 9 in the printing position. The said means are so constructed as not to interfere with the pawl acting upon the ratchet wheel which actuates it, thus permitting the grouping of a pawl acting upon the 75 ratchet of a digit wheel, and the means for controlling the pawl of the adjoining wheel, about the same ratchet wheel. 80

The invention consists primarily in a numbering head embodying therein a shaft, a plurality of digit wheels, rotatably mounted upon said shaft, a ratchet wheel rotatable with each of said digit wheels, a holding pawl coöperating with each of said ratchet wheels, a plurality of means normally operative to prevent movement of said pawls respectively, means movable with each digit wheel of lower denomination and operative upon said means acting upon the pawl of the ratchet wheel of the digit wheel of next 85 higher denomination whereby said means is made inoperative during the transfer operation from said wheel of lower denomination to said wheel of higher denomination 90 and actuating means for said digit wheels; 100 105 110

and in such other novel features of construction and combination of parts as are herein-after set forth and described and more particularly pointed out in the claims hereto appended.

5 Referring to the drawings:—Figure 1 is a rear elevation upon a large scale of a numbering head embodying my invention; Fig. 2 is a section on the line 2—2 of Fig. 1; Fig. 3 is a plan view of said numbering head; Fig. 4 is a side view thereof; Fig. 5 is a side view of the tens digit wheel; Fig. 6 is a front view thereof; Fig. 7 is a view of the other side thereof; Fig. 8 is a detail view in perspective showing two of the adjacent pawl locking levers; Fig. 9 is a fragmentary view of the shaft upon which said levers are mounted; Fig. 10 is a side view of the units digit wheel broken away, showing the tens wheel and the pawl operative thereon, the operation of said mechanism being indicated in dotted lines; Fig. 11 is a front view of the units digit wheel; and Fig. 12 is a side view of one of the digit wheels above the tens wheel.

25 Like letters refer to like parts throughout the several views.

In the embodiment of my invention shown in the drawings, *a* indicates the frame of the machine having mounted therein a shaft *b* upon which a sequence of digit wheels *c*—*c'*—*c*²—*c*³—*c*⁴—*c*⁵— and *c*⁶ are rotatably mounted, each of these digit wheels having upon the periphery thereof, ten characters from 0 to 9. Each of said digit wheels carries a ratchet wheel *d*—*d'*—*d*²—*d*³—*d*⁴—*d*⁵—*d*⁶ rotatable therewith, by means of which the wheels are held in proper alinement and such of the wheels as are mechanically actuated are turned. In numbering heads of this character it is a common practice to have only the wheels of lower denomination actuated by power, as after 100,000 or more sheets have been numbered, wheels of denominations of 100,000 or more may be conveniently turned by hand without materially interfering with the capacity of the machine. The construction of the digit wheels themselves is that ordinarily employed in numbering heads of this character, my invention relating more particularly to the means for controlling the movement of said wheel as distinguished from the construction of the wheels themselves.

55 In the type of machine shown in the drawings, those digit wheels which are mechanically actuated are severally acted upon by a sequence of pawls *e*—*e'*—*e*²—*e*³—*e*⁴ carried by a hub common to all such pawls said hub being rotatably mounted upon a shaft *e*⁶ carried by an oscillatory frame *e*⁷. Said hub *e*⁵ is acted upon by a spring *e*⁸ having a normal tendency to thrust all of said pawls toward the ratchet wheels with which said pawls are adapted

to coöperate. Each of said ratchet wheels has a depression therein as *f* into which the pawl coöoperating with said ratchet is adapted to drop upon the transfer operation to bring the pawl acting upon the ratchet 70 of the wheel of next higher denomination into operative engagement therewith. The said swinging frame *e*⁷ is actuated in the usual manner by means of the plunger *g*. This manner of actuating the wheels is old 75 and well known in this art and any other desired mechanism for actuating the digit wheels in arithmetical progression may be substituted therefor without departing from the spirit and scope of the invention.

80 Acting upon the ratchet wheels *d*—*d'*—*d*²—*d*³—*d*⁴—*d*⁵—*d*⁶ respectively are spring pressed pawls *h*—*h'*—*h*²—*h*³—*h*⁴—*h*⁵—*h*⁶ mounted upon a shaft *i* extending parallel with the shaft *b*. These pawls act as a 85 drag to prevent over-running of the digit wheels and at the same time serve to bring the wheels into alinement. In case of slight over-running of the wheel the said wheel will be brought back to its proper alined 90 position by the impact of the pawl with the ratchet tooth which it will engage upon the succeeding actuation of the said ratchet wheel. The use of such pawls and ratchet wheels is old and well-known in this art. 95

100 Heretofore locking means operative upon each digit wheel, have been used to prevent any, except a timely, turning of said wheels respectively. Such locking means, however, have necessitated a special construction of the digit wheel and the employment of independent locking means acting directly upon said wheels. By my present invention, I obviate the necessity for the use of such independent locking means acting upon the digit wheels, by the provision of means normally acting to hold each of the several pawls *h*'—*h*²—*h*³—*h*⁴—*h*⁵—*h*⁶ against displacement by the ratchet wheel with which they severally coöperate, and thus prevent any but a timely turning of 110 these digit wheels in either direction through the usual ratchet mechanism. In the form of the invention shown, I secure this result by providing each of the pawls *h*' to *h*⁶ inclusive with a short arm or heel *j*'—*j*²—*j*³—*j*⁴—*j*⁵—*j*⁶ projecting below the shaft *i*. 115

120 Mounted upon the shaft *l* are a series of stop levers *k* projecting between adjacent digit wheels respectively and provided with a laterally extending abutment *k*' normally projected within the path of the arm or heel of the locking pawl operative in connection with the digit wheel of next higher denomination. Each of these stop levers is the same 125 as every other and it is therefore unnecessary to refer to the several levers separately. These levers *k* are each loosely mounted upon the shaft *l* and are severally acted upon by a spring *k*² having a normal tend- 130

ency to position said levers so that they will be operative to prevent movement of that pawl, the movement of which is controlled thereby.

- 5 The abutment k' and that portion of the lever k adjacent thereto is preferably reduced in height as compared with the remaining portions of said lever to afford clearance above said abutment, and said 10 lever is stepped or off-set at K^3 as shown to afford that clearance necessary for the oscillations of the holding pawl when the lever controlling same is depressed.

In connection with each digit wheel, I employ means movable therewith which means are adapted to act upon the lever k operative upon the pawl of the wheel of next higher denomination, in a manner to release said pawl during that interval when 15 a movement of the wheel of next higher denomination is necessary to secure the desired carrying or transfer operation. This means will vary according to the construction of the head with which the invention is used. 20 In the form of numbering head shown in the accompanying drawings, this means comprises a single cam tooth rotatable with the digit wheel and adapted to operatively engage and depress the locking lever for the 25 pawl of the wheel of next higher denomination when the digit 9 is in the printing position upon the wheel of lower denomination. In the form of numbering head shown in the accompanying drawings, it is desirable 30 by reason of the form of actuating mechanism used to construct the units digit wheel and its appurtenances and the tens digit wheel and its appurtenances differently from each other and from the remaining 35 wheels. This difference of construction is due to the fact that the tooth e' is of a height not to afford sufficient clearance to permit the use of a high tooth upon the ratchet wheel d' and because it is desirable 40 for structural reasons to provide the units digit wheel c with a separate cam disk for actuating the lever k operative upon the tens wheel.

The actuating means for the lever k acting upon the heel j is a disk m carried by and rotatable with the units digit wheel c and its ratchet d . This disk m has thereon a single tooth m' of a height sufficiently greater than that of the teeth of the ratchet 55 wheel d to throw the abutment k' of the lever k out of engagement with the pawl h' when the digit 9 of the units wheel is in the printing position.

The tens digit wheel has its ratchet wheel 60 d' upon the side thereof toward the units wheel and upon the opposite side thereof, or between it and the hundreds wheel, it carries a disk n having thereon a single tooth n' adapted to engage and depress the locking 65 lever k operative upon the pawl h^2 . Each

of the remaining ratchet wheels d^2 to d^5 have thereon a single high tooth o adapted respectively to engage the locking lever k operative upon the pawl of the wheel of next higher denomination to release said 70 pawl when the digit 9 of the wheel of lower denomination is in the printing position.

In setting a numbering head having locking means for each of the digit wheels, it is desirable that the locking means for any 75 wheel may be released to permit the manual turning of that wheel and also that the locking means for all of the wheels may be simultaneously released so as to permit the turning of any wheel. By thrusting a knife-blade between any two locking pawls h to h^6 80 the abutment k' of the lever k may be pressed downwardly to release any one wheel.

To permit all of the wheels to be simultaneously released, I form in the shaft l a circumferentially extending slot p in which is movably mounted a projection k^4 upon each of the levers k . When the said levers are in their normal position so as to prevent 90 movement of their respective pawls said projections k^4 will bear against one end of the slot p in the shaft l . Hence, the length of said slot will permit that movement of any of said levers upon said shaft necessary 95 to release its pawl. The shaft l is rotatably mounted in the frame a and one end thereof is provided with an operating handle g so that when it is desired to simultaneously release all of the pawls h to h^6 , all of the 100 levers k may be forced downwardly out of the operative relation to their respective pawls by a partial rotation of said shaft l .

The various levers k project between the digit wheels into operative range of the 105 high cam teeth $m'-n'$ and o operative thereon, their upward movement preferably being defined by the projection k^4 engaging the end of the slot p . These levers k are so assembled in the machine as to occupy 110 a space ordinarily existing in numbering heads of this type, thus not requiring any increase either in the height or width of the numbering head.

The operation of the herein described 115 numbering head is substantially as follows, assuming that the head is set to begin a run with the number "1":—With each actuation of the plunger g , the frame e^7 will be oscillated and the pawl e will upon the return 120 movement thereof engage a tooth of the ratchet d and turn the digit wheel c one-tenth of a revolution. As the digit "9" is being brought to the printing position, the high cam tooth n' upon the disk n will engage and depress the lever k adjacent the units wheel and force the abutment k' thereof downwardly so as to bring it below the arm or heel j' of the pawl h' operative 125 upon the tens wheel. Before the digit "9" 130

comes to the printing position all of the levers k will be elevated so that their respective projections k' will be in the paths of the respective arms or heels j' to j and thus hold all of the wheels of a denomination above the units wheel against movement. Upon the next actuation of the frame e^7 , when the pawl h' is free to move, the pawl e will drop into the recess f of the 10 units digit wheel and bring the pawl e' into operative engagement with the ratchet d' so that upon the return movement of said frame, the units wheel c and the tens wheel c' will turn simultaneously, the remaining 15 digit wheels being locked in position by their respective holding pawls. This locking of the digit wheels results from the several pawls h^2 to h^6 being held against oscillatory movement and in operative engagement with their respective ratchet wheels. When the digit "9" upon both the units and the tens digit wheels are in the printing position, the high cam teeth m' and n' will simultaneously depress the levers k upon 20 which they are operative so that upon the next actuation of the frame e^7 the pawls $e-e'$ will drop into the openings f of the units and the tens wheel and bring the pawl e^2 into operative engagement with the ratchet 25 d^2 of the hundreds wheel c^2 , thus simultaneously moving the units, tens and hundreds wheels. When the digits "9" of the units, tens and hundreds wheels are in the printing position, the wheel tooth o upon the 30 ratchet wheel d^2 will depress the lever k between the hundreds and the thousands wheel simultaneously with the depression of the levers k operative in connection with the wheels of lower denomination and upon the 35 next actuation of the frame e^7 the units, tens, hundreds and thousands wheel will all be turned while the wheels of higher denomination remain locked. This operation is repeated in connection with each digit 40 wheel of higher denomination with the arithmetical progression of the machine, it being impossible to turn any digit wheel unless all of the wheels of lower denomination have the digit "9" in the printing position. While 45 the bringing of the digit "9" of any digit wheel in the printing position will release the locking means for the wheel of next higher denomination, unless all of the 50 wheels of lower denomination than that released have the digit "9" in the printing position, said released wheel cannot be turned. This results because there will be disposed between the released wheel of higher denomination and the units wheel, or between 55 it and those wheels which are turned during the actuation of the machine, a digit wheel which is locked against movement. For example, if in the progression of the 60 machine the number for which the machine is set is 9139 the ratchets d' and d^2 will both

be free to move and yet upon the next actuation of the machine only the units and tens wheels will turn, the ratchet d^2 of the hundreds wheel being locked because the tens wheel does not have the digit "9" in the 70 printing position. Therefore, while the locking mechanism of the thousands wheel is inoperative to prevent accidental movement thereof, such movement can be imparted thereto only through the adhesion of 75 the hundreds wheel thereto and this hundreds wheel is locked against movement. As a result of this condition so long as any wheel between a released wheel and the units wheel is locked, there can be no accidental skipping of the machine. 80

If it be desired to set a single digit wheel, the lever k , operative upon the pawl thereof, may be depressed so as to permit the free turning of the wheel. If it be desired to 85 re-set the entire head, the handle q is swung to turn the shaft l and simultaneously depress all of the levers k , thus permitting any wheel to turn.

By utilizing the holding pawls as a portion of the means for locking the several digit wheels, the function of these pawls as holding pawls is not interfered with; and even when the shaft l is turned to permit the setting of the head, these pawls will still act 95 as a drag to control the movement of the respective digit wheels and facilitate the accurate hand turning thereof. 90

I believe it to be broadly new to provide a numbering head including therein means 100 whereby movement of the holding pawls acting upon the ratchet wheel, is prevented in a manner to lock the said ratchet wheel, and the digit wheel under the control of said ratchet wheel, against movement in 105 either direction, and I intend to claim such broadly.

It is not my intention to limit the invention to application to the specific type of 110 numbering head shown in the accompanying drawings, as it is apparent the invention is applicable to any type of head wherein each digit wheel has associated therewith a ratchet wheel having simultaneous rotary movement therewith. 115

Having described the invention what I claim as new and desire to have protected by Letters Patent is:—

1. A numbering head embodying therein a shaft, a plurality of digit wheels rotatably mounted upon said shaft, a ratchet wheel rotatable with each of said digit wheels, a holding pawl co-operating with each of said ratchet wheels, a plurality of means normally operative to prevent movement of said pawls respectively, means movable with each digit wheel of lower denomination and operative upon said means acting upon the pawl of the ratchet wheel of the digit wheel of next higher denomination whereby said 120 125 130

means is made inoperative during the transfer operation from said wheel of lower denomination to said wheel of higher denomination, and actuating means for said digit wheels.

2. A numbering head embodying therein a shaft, a plurality of digit wheels rotatably mounted upon said shaft, a ratchet wheel rotatable with each of said digit wheels, a holding pawl coöperating with each of said ratchet wheels, a plurality of means normally operative to prevent movement of said pawls respectively, means movable with each digit wheel of lower denomination and operative upon said means acting upon the pawl of the ratchet wheel of the digit wheel of next higher denomination whereby said means is made inoperative during the transfer operation from said wheel of lower denomination to said wheel of higher denomination, a transfer mechanism actuating directly upon the several digit wheels and a main actuating mechanism therefor.

3. A numbering head embodying therein a shaft, a plurality of digit wheels rotatably mounted adjacent each ratchet wheel respectively and having a laterally extending abutment engaging the arm or heel of the pawl coöperating with the adjacent ratchet wheel whereby movement of said pawl is normally prevented, each of said levers having a stepped or offset portion at one side of said abutment whereby clearance is afforded for the movement of the pawl operative upon the ratchet wheel adjacent said lever, means movable with each digit wheel of lower denomination and operative upon said means acting upon the pawl of the ratchet wheel of the digit wheel of next higher denomination whereby said means is made inoperative during the transfer operation from said wheel of lower denomination to said wheel of higher denomination, and actuating means for said digit wheels.

3. A numbering head embodying therein
25 a shaft, a plurality of digit wheels rotatably mounted upon said shaft, a ratchet wheel rotatable with each of said digit wheels, a holding pawl coöperating with each of said ratchet wheels having an arm or heel thereon, means normally positioned in the path of the arm or heel upon each of said pawls whereby movement of said pawls respectively is prevented, means movable with each digit wheel of lower denomination and operative upon said means acting upon the pawl of the ratchet wheel of the digit wheel of next higher denomination whereby said means is made inoperative during the transfer operation from said wheel of lower denomination to said wheel of higher denomination, and actuating means for said digit wheels.

for said digit wheels.

6. A numbering head embodying therein
90 a shaft, a plurality of digit wheels rotatably mounted upon said shaft, a ratchet wheel carried by and rotatable with each of said digit wheels, a holding pawl coöperating with each of said ratchet wheels, a plurality
95 of levers positioned between adjacent ratchet wheels and normally operative to prevent movement of said pawls respectively, a cam carried by and rotatable with each said digit wheel and adapted to actuate said levers respectively when the character "9" of the digit wheel is in the printing position whereby a lever of a wheel of one denomination is made inoperative during the transfer operation from said wheel
100 to the wheel of the next denomination, and actuating means for said digit wheels.

4. A numbering head embodying therein a shaft, a plurality of digit wheels rotatably mounted upon said shaft, a ratchet wheel rotatable with each of said digit wheels, a holding pawl coöperating with each of said ratchet wheels, each of said pawls having an arm or heel thereon, a plurality of levers 45 mounted adjacent each ratchet wheel respectively and having a laterally extending abutment engaging the arm or heel of the pawl coöperating with the adjacent ratchet wheel whereby movement of said pawl is normally 50 prevented, means movable with each digit wheel of lower denomination and operative upon said means acting upon the pawl of the ratchet wheel of the digit wheel of next 55 higher denomination whereby said means is made inoperative during the transfer operation from said wheel of lower denomination to said wheel of higher denomination, and 60 actuating means for said digit wheels.

5. A numbering head embodying therein a shaft, a plurality of digit wheels rotatably mounted upon said shaft, a ratchet wheel 110 carried by and rotatable with each of said digit wheels, a holding pawl coöperating with each of said ratchet wheels, each of said pawls having an arm or heel thereon, a plurality of levers 115 arranged between adjacent digit wheels, and normally adapted to engage said arm or heel of said pawls to prevent movement of said pawls respectively, a cam carried by and rotatable with each digit wheel and adapted to actuate said levers respectively when the character "9" 120 of the digit wheel is in the printing position whereby a lever of a wheel of one denomination is made inoperative during the transfer operation from said wheel to the wheel of 125 the next denomination, and actuating means for said digit wheels.

6. A numbering head embodying therein

5. A numbering head embodying therein a shaft, a plurality of digit wheels rotatably mounted upon said shaft, a ratchet wheel 130

and a cam having a single riser thereon carried by and rotatable with the units digit wheel, a ratchet wheel upon one side of the tens digit and a cam having a single riser 5 on the other side thereof between it and the hundreds wheel, a ratchet wheel upon all wheels of a denomination above the tens wheel having a high tooth or riser, a holding pawl coöperating with each of said ratchet 10 wheels, said pawls each having an arm or heel thereon, a lever mounted adjacent said riser upon the units wheel, the tens wheel and each ratchet wheel of each of the digit wheels of denominations higher than the 15 tens, said levers being normally adapted to engage said arms or heels and prevent movement of said pawls, said risers respectively being adapted to make said levers inoperative with relation to their respective pawls 20 when transferring from a wheel of one denomination to a wheel of next denomination and actuating means for said digit wheels.

9. A numbering head embodying therein a digit wheel having a ratchet wheel upon one 25 side thereof one of the teeth of said ratchet wheel being higher than the others in combination with a holding pawl acting upon said ratchet wheel and controlling means for said holding pawl adapted to be acted upon 30 by said high tooth.

10. A numbering head embodying therein a pivotal pawl having a head adapted to engage a ratchet wheel and an arm or heel projecting from point of pivotal support in 35 a direction away from said head in combination with means coöperating with said arm or heel to prevent oscillatory movement of said pawl, and a ratchet wheel provided with means adapted to impart a timely actuation to said last named means.

11. A numbering head embodying therein a shaft, a plurality of digit wheels rotatably mounted on said shaft, a ratchet wheel rotatable with each of said digit wheels, a 45 holding pawl coöperating with each of said ratchet wheels, said pawls each having an arm or heel thereon, a shaft parallel with said first named shaft, a plurality of levers loosely mounted thereon adjacent each 50 ratchet wheel, said levers each having a laterally extending abutment adapted to engage the arm or heel of the pawl operative upon the adjacent ratchet wheel whereby movement of said pawl is normally prevented, means movable with each digit wheel 55 whereby the lever acting upon the pawl of the adjoining digit wheel is made inoperative during the transfer operation, and actuating means for said digit wheels.

60 12. A numbering head embodying therein a shaft, a plurality of digit wheels rotatably mounted on said shaft, a ratchet wheel rotatable with each of said digit wheels, a holding pawl coöperating with each of said 65 ratchet wheels, said pawls each having an

arm or heel thereon, a shaft parallel with said first named shaft, a plurality of levers loosely mounted thereon adjacent each ratchet wheel, said levers each having a laterally extending abutment adapted to engage the arm or heel of the pawl operative upon the adjacent ratchet wheel whereby movement of said pawl is normally prevented, means movable with each digit wheel whereby the lever acting upon the pawl of the adjoining digit wheel is made inoperative during the transfer operation, means whereby all of said levers may be simultaneously actuated to release all of said pawls and actuating means for said digit wheels. 75

13. A numbering head embodying therein a shaft, a plurality of digit wheels rotatably mounted on said shaft, a ratchet wheel rotatable with each of said digit wheels, a holding pawl coöperating with each of said ratchet wheels, said pawls each having an arm or heel thereon, a movable shaft parallel with said first named shaft, a plurality of levers loosely mounted thereon, adjacent each ratchet wheel, said levers each having a laterally extending abutment adapted to engage the arm or heel of the pawl operative upon the adjacent ratchet wheel whereby movement of said pawl is normally prevented, means movable with each digit wheel whereby the lever acting upon the pawl of the adjoining digit wheel is made inoperative during the transfer operation, 85
